(57) **CLAIM**

The ornamental design for a turning aid air mattress with a left and a right inflatable chamber, as shown and described.

DESCRIPTION

The patent or application file contains at least one drawing executed in color. Copies of this patent or patent application publication with color drawing(s) will be provided by the Office upon request and payment of the necessary fee.

1. Turning aid air mattress with a left and a right inflatable chamber

1.1 is a perspective view of a turning aid air mattress with a left and a right inflatable chamber.

1.2 is a perspective view thereof with the right side chamber inflated.

1.3 is a perspective view thereof with the left side chamber inflated.

The broken lines illustrating features and the areas within them depict portions of the turning aid air mattress with a left and a right inflatable chamber that form no part of the claimed design.
